Inventor.

UNITED STATES PATENT OFFICE.

THOMAS SHAW, OF PHILADELPHIA, PENNSYLVANIA.

IMPROVEMENT IN PLANING-MACHINES.

Specification forming part of Letters Patent No. 135,941, dated February 18, 1873.

To all whom it may concern:

Be it known that I, THOMAS SHAW, of the city and county of Philadelphia, Pennsylvania, have invented a new and Improved Planer-Bar; and I hereby declare the following to be a full, clear, and exact description of the same, reference being had to the accompanying drawing and to the letters of reference marked thereon.

My invention consists in the employment of a bar in the manner and for the purpose as hereafter described. The object of the invention is to enable ordinary planing-machines to reach through work, and perform operations similar to shaping or slotting machines.

In order to enable others to use and practice my invention, I will proceed to describe its construction and operation.

On reference to the accompanying drawing, which forms part of this specification, Figure 1 is a side view of section of an ordinary planer with the invention attached, and Fig. 2 is an end view of planer-bar.

a, Fig. 1, is the ordinary planer-bed, upon which the work is bolted. *b* is the side braces that support the ordinary tool-carriage *g*. *c* is the planer-bar, supported upon clamp-box *f*, and is forked and pivoted at its back end, as shown at *d*, to cross-bar *e*, and is provided on its outer end with a cutting-tool, *k*. The

socket *i* is secured in the desired position by the ordinary tool-post *l*, and is screwed at its lower end into yoke *h*, said yoke being pivoted, as shown in Fig. 2, to clamp-box *f*. The cross-bar *e* is pivoted on its outer ends to body of planer by means of center-bolts run through sides of braces *b*, all for the purpose as hereafter described.

It will be observed that the bar *c* has, at its outer end, all the vertical and horizontal movement that the feed-carriage *g* is susceptible of; and that the feed of planer will operate this bar; and that, by reason of the bar's projecting length it is capable of reaching through work equal to one-third the length of planer-bed; and that, by reason of the end-thrust character of the bar-forcing cutting-tool, it is capable of taking a cut equal to full capacity of planer; all of which are great and valuable features and additions to the planing-machine.

What I claim, and desire to secure by Letters Patent, is—

The combination, as herein described, of the planer-bar *c* with the planing-machine.

THOMAS SHAW.
